UNITED STATES PATENT OFFICE.

JOHN PEARCE ROE, OF LONDON, ENGLAND, ASSIGNOR TO THE ROPEWAYS
SYNDICATE, LIMITED, OF SAME PLACE.

RUNNING AND CARRYING CABLE.

SPECIFICATION forming part of Letters Patent No. 530,902, dated December 11, 1894.

Application filed January 30, 1894. Serial No. 498,443. (No model.)

To all whom it may concern:

Be it known that I, JOHN PEARCE ROE, a subject of the Queen of Great Britain and Ireland, residing at 150 Leadenhall Street, in the city of London, England, have invented 5 Improvements in Apparatus for Transporting Loads by Means of Traveling Ropes or Cables, of which the following is a specification.

10 In the specification of Letters Patent granted to me, No. 438,949, of October 21, 1890, I have described constructions of apparatus for transporting loads by means of traveling ropes in which an adjustable grooved block 15 or blocks provided with internal projections (or recesses) is or are employed to engage with the helically twisted strands of the rope for the purpose of fixing the apparatus to the said rope. To render the apparatus effective 20 whether ascending or descending gradients, one of the grooved blocks, when two are used, is provided with a projection arranged to engage under a strand of the rope and prevent the block slipping longitudinally in one direction upon the rope, while the other block 25 is provided with a projection adapted to act in a similar manner and prevent its block slipping in the opposite direction on the rope, one projection only being effectively engaged 30 with the rope at a time. When one adjustable block only is used, its groove is provided with oppositely arranged projections, that or those on one side coming into operation when the apparatus is ascending a gradient, and 35 that or those on the other side coming into operation when the apparatus is descending a gradient.

In each of the above mentioned arrangements, the projection that is, (for the time being,) out of action, is liable under some circumstances to ride upon or assume such a position relatively to the strand of the rope adjacent thereto as to materially interfere with the proper engagement of the other projection with the rope, and an object of this invention is to obviate this disadvantage. For this purpose I so form and arrange the grooved block or blocks, or parts carrying the projec-

tions, that only one projection at a time will be caused by the action of the load carried 50 to engage with or bear against a strand of the rope by the action of the load carried. For this purpose the groove in the under side of each block is made doubly inclined or of a circular arc shape in the direction of its 55 length, so that when the block is turned on the rope as a bearing, in one direction, the projection within its groove will be brought into proper position to engage a strand of the rope, and when turned in the opposite direction such projection will be turned into its 60 inoperative position and clear of the strands of the cable so that it cannot then interfere with the proper action of the operative projection in another block. In a modified construction, the projection is carried by a movable holder and held in position by a spring.

In the accompanying drawings, Figures 1 and 2 are vertical sections illustrating my improved forms of grooved blocks. Figs. 3, 4 70 and 5 are side elevations illustrating the application of such blocks. Figs. 6 and 7 show in side and end elevation respectively, a form of grooved block with movable projection. Figs. 8 and 9 are end and under side views 75 respectively, showing part of a grooved block with an improved form of projection therein.

Referring to Figs. 1 and 2, 1 is a gripping block of the kind referred to having in its under side a V-shaped groove 2 which according to this invention, instead of being made straight as in my former constructions of such blocks, is made either doubly inclined in the direction of its length as shown in Fig. 1, or of circular arc shape as shown in Fig. 2, so 80 that such block can turn or oscillate upon the rope as a bearing, 3 being the projection formed on one side of such groove.

Figs. 3 and 4 show two such grooved blocks applied to a frame or backbone 4 the projection 90 3 on the front block 1 being at the forward portion of the groove therein and that (3*) on the rear block 1* being at the rearward portion of the groove in such block.

With this construction assuming that the 95 traveling rope 5 is running in the direction

of the arrow, and that the portion thereof on which the apparatus is applied commences to move in a downward direction, the frame 4, under the action of the load carried thereby, 5 will move longitudinally for a short distance relatively to the blocks and rock or turn them on the rope into the positions shown in Fig. 3, so that the projection 3 on the inner side of the forward block will be brought into the 10 proper position to engage a strand of the rope, while the projection 3* on the inner side of the rearward block will be raised clear of the rope as shown, and thus rendered inoperative thereon. When the rope becomes 15 inclined in the opposite direction, although traveling in the same longitudinal direction as before, the frame 4 will move a short distance in the opposite or backward direction and automatically move the blocks into the 20 positions shown in Fig. 4, in which the projection on the rearward block will be brought into the operative position and that on the forward block into the inoperative position. The movement of the blocks may be effected 25 by pins 6 carried by the ends of the frame and extending through slots 7 formed in the corresponding blocks. In this way the projection that is for the time being out of action is prevented from riding or assuming 30 such a position relatively to a strand of the rope as to interfere with the proper engagement of the other projection with the rope.

Fig. 5 shows an arrangement in which one rocking or oscillating block 1 only of the kind 35 described is employed, the other end of the frame 4 being connected to an ordinary V-grooved block 8 that merely serves as a support therefor, the connection between the two being preferably such as to admit of slight 40 turning movement of the block relatively to the frame, as when passing over a rope sheave or pulley. In this arrangement each grooved end of the block 1 is provided with a projection, one, say 3, being adapted to come into 45 action on an ascending gradient, and the other (3*) on a descending gradient, the one that is for the time being inoperative being held clear of the rope as before.

Figs. 6 and 7 show a modified form of 50 grooved block in which the projection 3 is carried by a movable slide or holder 9 acted upon by a spring 10, the arrangement being such that the said projection will always be in a position to engage the rope when moved 55 thereon in the proper direction, but will be pressed upon the rope only by the spring, so that it is free to yield in an upward direction when inoperative and thus cannot interfere with the proper action of the operative projection in another block.

When the projections are of such a form as to work against the under side of the strands of the rope, as described in my said former specification, they are liable to become wedged

so tightly in place, after working on a steep 65 gradient, as to interfere with their ready disengagement from the rope at the required times. To obviate this disadvantage I make each projection with a flat or curved vertical face 3^a as shown in Figs. 8 and 9, adapted to 70 act laterally against a strand of the rope instead of vertically against its under side, the said face, when flat, being made inclined to a vertical plane α α , passing longitudinally through the groove in the block. 75

What I claim is—

1. Apparatus for transporting loads by means of a traveling rope, comprising a frame, grooved blocks carried thereby and adapted to take upon a traveling rope, and projections carried by said blocks and projecting into the grooves therein, the portion of each block carrying a projection being capable of movement to and from said rope while the remaining portion of said block bears upon 85 said rope substantially as described for the purpose specified.

2. In apparatus for transporting loads by means of traveling ropes, a block formed with a groove or recess of bent form in longitudinal section and having one or more projecting parts adapted to engage with the helically twisted strands of a cable substantially 90 as herein described for the purpose specified.

3. In apparatus for transporting loads by means of traveling ropes, the combination of a frame or backbone, and a block formed with a groove or recess of wedge shape in cross section and of bent form in longitudinal section so as to be capable of rocking or turning 100 on the cable to which it is applied, substantially as herein described for the purpose specified.

4. Apparatus for transporting loads by means of traveling ropes, comprising a frame, 105 and a block adjustably connected therewith and having one or more projecting parts adapted to engage with the helically twisted strands of a rope, the groove in said block being doubly inclined in the direction of its 110 length, substantially as herein described for the purpose specified.

5. Apparatus for transporting loads by means of traveling ropes comprising a frame, front and rear blocks each connected by a pin 115 and slot connection with said frame and formed with a groove of bent form in the direction of its length, and oppositely arranged projections each adapted to engage with a helically twisted strand of a rope when moved 120 longitudinally thereon, one of said projections being located in the forward grooved portion of said front block, and the other in the rearward grooved portion of said rear block substantially as herein described for 125 the purpose specified.

6. In apparatus for transporting loads by means of traveling ropes, a block formed with

a groove to fit over a rope and provided with a projection formed with a flat or curved vertical active face inclined to a vertical plane passing longitudinally through the groove in said block and adapted to engage the side of a helically twisted strand of a rope substantially as herein described for the purpose specified.

In testimony whereof I have signed my

name to this specification in the presence of 10 two subscribing witnesses.

JOHN PEARCE ROE.
